UNITED STATES PATENT OFFICE.

OWEN W. CALLAHAN, OF CLEVELAND, OHIO, ASSIGNOR TO THE OWEN BUCKET COMPANY, A CORPORATION OF OHIO.

GRAB-BUCKET.

997,748.

Specification of Letters Patent. Patented July 11, 1911.

Application filed September 13, 1907, Serial No. 392,818. Renewed March 6, 1911. Serial No. 612,716.

To all whom it may concern:

Be it known that I, OWEN W. CALLAHAN, a citizen of the United States, residing at Cleveland, in the county of Cuyahoga and 5 State of Ohio, have invented certain new and useful Improvements in Grab-Buckets; and I do hereby declare the following to be a full, clear, and exact description of the invention, such as will enable others skilled 10 in the art to which it pertains to make and use the same.

This invention relates to grab buckets and especially to grab buckets of the clam shell type operated on the block and falls or 15 tackle principle.

One of the objects of the invention is to provide a grab bucket which has great digging power and is strong and durable.

A further object is to provide a bucket 20 which is operated on the block and tackle principle and has upper and lower closing blocks each provided with a multiplicity of sheaves, the blocks being arranged and connected in a manner such that all the dif- 25 ferent bights or sections of the closing cable reeved about such sheaves have fair leads, and the sections extending upwardly from the outer or end sheaves of the lower closing block are in substantially the center 30 plane of the bucket, so that the bucket will be plumb at all times when suspended by the closing cable.

A still further object is to provide simple but effective means whereby the bucket may 35 be suspended and carried independently of the closing cable so that the latter may be relieved of the load after the bucket is closed.

These and other objects are accomplished 40 by my invention which may be briefly summarized as consisting in certain novel details of construction and combinations and arrangements of parts which will be described in the specification and set forth in 45 the appended claims.

In the drawings, Figure 1 is a vertical sectional view with parts in elevation, of a bucket constructed in accordance with my invention; Fig. 2 is a side elevation of the 50 bucket showing more clearly the arrangement of the upper and lower closing blocks with respect to each other and with respect to the parts to which said blocks are respectively connected.

55 The bucket is provided with two jaws

1-1 which are pivotally connected through the medium of a shaft 2, and hinging arms 3, which are fastened to the inner or adjacent portions of the jaws and loosely engage the shaft 2. The bucket also includes a 60 head comprising an opening block 20 having a single sheave, and a rod 15 passing through side plates of the head and arranged parallel to the shaft 2. The head is connected to the jaws by means of arms 22 65 which loosely engage the outer ends of the rod 15 and are pivotally connected to the outer corners of the jaws.

Great digging power is obtained with the present bucket by reason of the fact that I 70 employ a counterweight which is indirectly connected to the jaws, and a closing tackle including a lower closing block 5 and an upper closing block 16, each having a multiplicity of sheaves, the digging power being 75 dependent upon the weight of the counterweight, and also the number of sheaves of the closing tackle. By employing these parts, when the bucket is being closed on the material, the upper closing tackle is pulled 80 downward, instead of the lower block being pulled upward toward the upper block. In this case, the upper block 16 is suspended from the rod 15, and the lower block 5 is connected directly to the counterweight 4. 85

In employing a considerable number of sheaves in the closing tackle, as in the present case in which the lower block has four sheaves and the upper block three sheaves, the bights of the closing cable 23 which is 90 reeved about the sheaves, would ordinarily be inclined and would not have fair leads, and the portions of the cable extending upwardly from the two outer or end sheaves of the lower block would be on opposite sides 95 of the center plane of the bucket, with the result that the bucket would not hang plumb. To overcome these disadvantages, the lower block 5 is inclined with respect to the counterweight and is arranged at an angle such 100 that the portions of the cable 23 extending upwardly from the two outer sheaves and up through the guides carried by the bucket head have fair leads and are in substantially the center plane of the bucket. This arrangement will be apparent from a comparison of Figs. 1 and 2. Furthermore, the upper block is given a slightly greater inclination than the lower block, as indicated in Fig. 2 so as to cause the sheaves of the up- 105 110

per block to be slightly inclined with respect to and to cross the sheaves of the lower block so as to cause the bights of the cable extending from the sheaves of one block to 5 the sheaves of the other block to be substantially vertical and to have fair leads. The lower block is in this case secured to the counterweight by means of a pintle 8 passing through the cheek plates and division plates 7 of the lower block and through a series of lugs at the top of the counterweight and arranged in a row at the proper inclination to accomplish the results above stated. The cheek plates and division plates 10 which are arranged between the sheaves 6 in the usual manner extend downward into slots between the lugs of the counterweight, as shown in Fig. 2.

In order that the closing tackle may be 20 relieved of the load of the bucket and of the material in the bucket after the bucket jaws are closed, I have provided the following simple and very effective supporting mechanism for supporting the bucket with the 25 jaws in closed position. To support the bucket and its load independently of the closing tackle, I provide bail 9 which is loosely connected to the rod 15 in a manner such that there may be slight play between 30 the two, the bail 9 having at its ends which extend beneath the rod 15, suitable hooks 10. On the counterweight are pivotally connected a pair of bell crank levers having arms 11 which are adapted to engage the hooks 35 10, these bell crank levers being pivoted to the counterweight at 12—12 on opposite sides of the lower closing block 5. The bell cranks are also provided with outwardly extending arms 13 which when the counter- 40 weight is raised during the closing movements of the jaws, are adapted to be engaged by spring-like members 18, on the lower ends of depending arms 14 mounted on the rod 15, so as to rock the bell cranks 45 and swing the arms 11 in position to be engaged by the hooks 10 on the bail 9. Springs 19 attached to the bell cranks are adapted to bear on the top of the counterweight 4 and rock the bell cranks so as to 50 swing the arms 11 out of reach of the hooks 10 when the counterweight 4 is lowered slightly and when the arms 13 move away from the members 18. The arms 14 and downwardly projecting ends of bail 9 55 are held in proper relative positions by guides 17 secured to the arms 14 and projecting on opposite sides of the bail. With this construction, when the jaws are closed, the bell cranks are automatically swung to 60 positions such that the arms 11 may be engaged by the hooks 10 when the bail 9 is pulled upwardly, but when the bucket is supported independently of the bail, as when it is desired to open the buckets, and 65 as soon as the counterweight moves down-

ward slightly, the bell cranks automatically swing to positions such that the hooks of the bail will not interfere with the opening of the bucket jaws.

What I claim is:—

1. In a grab bucket, a pair of jaws pivotally connected together, a bucket head, arms connecting the head to the outer portions of the jaws, means for giving the bucket digging power comprising a counterweight at the pivotal axis of the jaws, and a closing tackle adapted to receive a closing cable and including a multiple sheave upper block connected to the head and a multiple sheave lower block connected to the counterweight, the bottom portion of the lower block being connected to the top portion of the counterweight, and the sheaves of the lower block being inclined to the axis of the counterweight at an angle such that the off-running portion of the cable extending upwardly from one of the end sheaves of the lower block is in substantially the center plane of the bucket.

2. In a grab bucket, a pair of jaws pivotally connected together, a bucket head, arms connecting the head to the outer portions of the jaws, a counterweight at the pivotal axis of the jaws, and a closing tackle adapted to receive a closing cable and including a multiple sheave upper block connected to the head, and a multiple sheave lower block connected to the counterweight, the blocks being relatively skewed so as to cause the portions of the cable between the two blocks to have fair leads, and the bottom of the lower block and the top of the counterweight having overlapping portions provided with aligned openings adapted to receive a connecting pin arranged at such an angle to the axis of the counterweight that the off running portion of the cable extending upwardly from one of the end sheaves of the lower block is in substantially the center plane of the bucket.

3. In a grab bucket, a pair of jaws pivotally connected together, a bucket head, arms connecting the head to the outer portions of the jaws, means for giving the bucket digging power comprising a counterweight at the pivotal axis of the jaws, and a closing tackle adapted to receive a closing cable and including a multiple sheave upper block connected to the head, and a multiple sheave lower block connected to the counterweight, said counterweight having at the top thereof a series of lugs arranged in a line at an angle to the axis of the counterweight, and said lower block having at the bottom thereof portions which overlap said lugs, and a pin extending through the lugs and portions of the block which overlap them and arranged at an angle such that the off running portion of the cable extends upwardly from one of the end sheaves of the lower block

at substantially the center plane of the bucket.

4. A bucket of the type set forth, comprising two jaws pivoted at the upper central portion to a counter-weight, a block and fall arrangement connected to said counter-weight for the purpose of closing the jaws and allowing the same to open with means such as catches connected to the counter-weight for engaging a vertically movable bail whereby the jaw are locked in closed position in combination with said bail.

5. A grab bucket comprising two jaws, a counter-weight, and said jaws pivoted at their upper portions thereto, a block and fall arrangement positioned diagonally with respect to said counter-weight and connected thereto, a cross-bar positioned in parallel relation to said counter-weight and above the counter-weight, and the block and fall arrangement connected thereto, pivotal links connecting the middle outer portions of said buckets to said cross-bar, a vertically movable bail pivoted to said cross-bar and provided with hooked lower ends, spring-pressed rocker means pivoted to said coun-

ter-weight and adapted to engage said hooks for locking said jaws in closed position.

6. A grab bucket comprising two jaws, a counter-weight, and said jaws pivoted at their upper portions thereto, a block and fall arrangement positioned diagonally with respect to said counter-weight and connected thereto, a cross-bar positioned in parallel relation to said counter-weight and above the counter-weight, and the block and fall arrangement connected thereto, pivotal links connecting the middle outer portions of said buckets to said cross-bar, depending hooks pivoted to said cross-bar, rocker means carried by said counter-weight and adapted to engage said hooks, and depending members secured to said cross-bar for automatically positioning said rocker means in engagement with said hooks.

Signed at Cleveland in the county of Cuyahoga and State of Ohio, this 3rd, day of September, 1907.

OWEN W. CALLAHAN.
